BALL TOY

Robert K. Ostrander, Jr., East Aurora, N.Y., assignor to Fisher-Price Toys, Inc., East Aurora, N.Y., a corporation of New York

Filed Feb. 28, 1967, Ser. No. 5,978

Term of patent 14 years

(Cl. D34—15)

FIG. 1 is a front elevational view of a ball toy showing my new design;

FIG. 2 is a side elevational view thereof, and

FIG. 3 is a top plan view thereof.

The opposite sides of FIGS. 1 and 2 being substantially similar to those shown.

I claim:

The ornamental design for a ball toy, substantially as shown and described.
